UNITED STATES PATENT OFFICE.

THOMAS F. BURKE, OF NEWCASTLE, PENNSYLVANIA.

FREIGHT-CAR.

SPECIFICATION forming part of Letters Patent No. 789,253, dated May 9, 1905.

Application filed February 23, 1904. Serial No. 194,748.

To all whom it may concern:

Be it known that I, THOMAS F. BURKE, a citizen of the United States, residing at Newcastle, in the county of Lawrence and State 5 of Pennsylvania, have invented certain new and useful Improvements in Freight-Cars, of which the following is a specification.

My invention relates to freight-cars for carrying grain, coal, broken stone, &c., and 10 has for one of its objects the provision of a car of the hopper-bottom type in which the upper part of the body is built of wood and the lower part of metal plates.

Another feature of my invention is that the 15 superstructure is supported by I-beams, the hopper-bottom being divided thereby and having spouts leading to the sides of the car, where the openings are formed for unloading the car.

20 The openings at the sides of the car are closed by means of sliding doors, the operating means for said doors being so arranged that they are opened and closed simultaneously.

25 The advantages of my invention will more fully appear hereinafter and by reference to the accompanying drawings, in which—

Figure 1 is a side view in elevation of my car; Fig. 2, a top plan view; Fig. 3, a bottom 30 view; Fig. 4, a cross-section through the car, and Fig. 5 an end view of the car made on a smaller scale.

In the drawings similar reference characters indicate corresponding parts throughout 35 the several views.

1 represents the center beams, which are preferably of the I-beam type and which are supported in any desired manner by the trucks of the car. (Not shown.)

40 2 represents the side sills, made of channel-iron and connected to the beams 1 by means of transverse I-beams 3 over the trucks and channel-beams 4 for the ends of the car-frame or bumpers.

45 5 represents braces for strengthening the joint between side sills 2 and transverse beams 3.

At each end of the car-frame is erected an upright frame consisting of end posts 6, hori-

zontal beams 7, connecting said posts intermediate of their length, and posts 8 for strengthening the middle of said beams 7. 9 represents ribs made of angle-iron secured to said beams 7 and extending obliquely downward below the central portion of side sills 2, the lower ends of said ribs being connected by horizontal plates 10.

11 represents bars connecting central beams 1 and plates 10 to brace the structure and also support the bottom of the hopper, which will 60 be described hereinafter. The ribs 9 are braced by means of angle-iron posts 12 and angular brackets 13.

14 represents ribs of angle-iron secured at one end to beams 7 intermediate of their ends 65 and extending downwardly parallel with ribs 9, said ribs 14 being braced and supported by uprights 15 and angular brackets 17.

The sides of the body of the car 18 are made, preferably, of timber and secured to upright 70 posts 19, of angle-iron, supported by side sills 2. At the lowest point, or immediately over plates 10, an opening is formed, as shown at 20, said openings being normally closed by means of doors 21, slidably mounted in grooved 75 guides 22.

The doors 21 are operated by means of arms 23, secured to a rock-shaft 24, journaled on center beams 1 and in the sides 18, one end of each arm 23 being connected by a link 25 with the bottom of the door 21 on the corresponding side of the car.

26 represents a socket on each arm 23 to receive the end of a handle 27 to swing the arm, it being understood that the operation 85 of swinging one of the arms also turns the rock-shaft 24 and the arm 23 on the opposite side of the car. It will be apparent by this construction that both doors may be opened or closed from either side of the car.

28 represents metal plates extending from the top of center beams 1 downwardly and slanting outwardly toward the openings 20, and 29 metal plates secured to ribs 9 and 14 and overlapped on plates 28.

30 represents base-plates supported by the lower ends of bars 11 and plates 10, secured to plates 28 and 29 and slanting outwardly to

the bottom of openings 20. This construction of the lower portion of the car, consisting of plates 28 and 29 and base-plates 30, forms a hopper on each side of center beams 1 and opening outwardly to the sides of the car.

Above the upper end of plates 29 the bottom 32 of the car is formed of timber secured to ribs 9 and 14, and the ends 33 are also formed of timber secured to posts 6 and resting on horizontal beams 7.

34 represents an angular metal plate secured over the center beams 1 to throw the contents of the car to the two side hoppers. 15 It will be apparent that plate 34 may be secured to plates 28 and form a continuous structure or may be secured independently from said plates 28, as desired.

It will be understood from the above description that my invention consists of the construction of a car-body of timber having in its lower portion hoppers extending to each side of the car, the hopper-openings being at the sides of the car and controlled by sliding doors operated simultaneously from either side of the car-body. This structure of car-body is sustained by a frame consisting of center beams, preferably made of the I-beam type, side sills, of channel-iron, upright end frames, and suitable braces, ribs, posts, &c. By constructing the sides 18 and bottom 32 of timber, while all below the bottom plates 32 are of metal, I obtain a car of maximum durability at a minimum cost and also avoid 35 the disfigurement incidental to metal-side cars caused by bulging and indentations. It will be also apparent that the details of construction hereinabove described may be altered without departing from the spirit of my invention.

Having thus described my invention, what I claim is—

1. In a freight-car, central beams, side sills, transverse beams connecting said central beams and side sills, upright frames on each end of the car, ribs extending longitudinally of the body of the car and secured to each end frame and the central beams and side sills, and the car-body supported by said ribs, substantially as shown and described.

2. In a freight-car, dump-openings at each side of the car, vertically-sliding doors to cover said dump-openings, arms pivotally mounted on each side of the car, links pivotally connecting each arm with the door on the corresponding side of the car, and means to operate said arms, substantially as shown and described.

ate said arms, substantially as shown and described.

3. In a freight-car, central beams of the I-beam type running the full length of the car, 60 side sills of channel-steel, transverse beams connecting the central beams and side sills, a frame erected at each end of the car, ribs extending longitudinally of the body of the car and supported by said frames and the central beams and side sills, and the car-body secured to said ribs, substantially as shown and described.

4. In a freight-car, central beams, side sills, transverse beams connecting said central 70 beams and side sills, a frame erected at each end of the car, ribs extending longitudinally of the body of the car and supported by said frames and the central beams and side sills, and a car-body supported by said ribs having 75 its bottom ends and sides made of timber and a hopper formed of metal plates, substantially as shown and described.

5. In a freight-car, central beams of the I-beam type, side sills made of channel-steel, 80 transverse beams connecting said central beams and side sills, a frame erected at each end of the car, ribs extending longitudinally of the body of the car and supported by said frames and the central beams and side sills, 85 and a car-body supported by said ribs having its bottom ends and sides made of timber and a hopper formed of metal plates, substantially as shown and described.

6. In a freight-car, dump-openings at each 90 side of the car, vertically-sliding doors to cover said dump - openings, a shaft suitably journaled, an arm secured to said shaft on each side of the car, links pivotally connecting each arm with the door on the corresponding side 95 of the car, and means to operate said arms, substantially as shown and described.

7. In a freight-car, a car-body suitably supported and built partly of metal plates and partly of timber, dump-openings at each side 100 of the car, a shaft journaled in the car-body, an arm secured to said shaft on each side of the car, links pivotally connecting each arm with the door on the corresponding side of the car, and means to operate said arms, substantially as shown and described.

In testimony whereof I hereto affix my signature in the presence of two witnesses.

THOMAS F. BURKE.
